[57] CLAIM

The ornamental design for a toy stuffed figure or similar article, as shown and described.

DESCRIPTION

FIG. 1 is a perspective view of a toy stuffed figure or similar article showing our new design;

FIG. 2 is a front elevation;

FIG. 3 is a side elevation taken from the left of FIG. 1, the right side being a mirror image thereof;

FIG. 4 is a top plan view;

FIG. 5 is a rear elevation;

FIG. 6 is a bottom plan view;

FIG. 7 is a perspective view of another design mode of the stuffed toy figure;

FIG. 8 is a front elevation of FIG. 7;

FIG. 9 is a side elevation taken from the left of FIG. 7, the right side being a mirror image thereof;

FIG. 10 is a top plan view of FIG. 7;

FIG. 11 is a rear elevation of FIG. 7;

FIG. 12 is a bottom plan view of FIG. 7;

FIG. 13 is a perspective view of another design mode of the toy stuffed figure;

FIG. 14 is a front elevation of FIG. 13;

FIG. 15 is a side elevation taken from the left of FIG. 13, the right side being a mirror image thereof;

FIG. 16 is a top plan view of FIG. 13;

FIG. 17 is a rear elevation of FIG. 13;

FIG. 18 is a bottom plan view of FIG. 13;

FIG. 19 is a perspective view of another design mode of the toy stuffed figure;

FIG. 20 is a front elevation of FIG. 19;

FIG. 21 is a side elevation taken from the left of FIG. 20, the right side being a mirror image thereof;

FIG. 22 is a top plan view of FIG. 19;

FIG. 23 is a rear elevation of FIG. 19;

FIG. 24 is a bottom plan view of FIG. 19;

FIG. 25 is a perspective view of another design mode of the toy stuffed figure;

FIG. 26 is a rear perspective view of FIG. 25;

FIG. 27 is a top plan view of FIG. 25; and

FIG. 28 is a bottom plan view of FIG. 25.
